UNITED STATES PATENT OFFICE.

CHARLES E. RANDALL, OF ATLANTA, GEORGIA, ASSIGNOR OF ONE-HALF
TO WILLIAM D. HOYT, OF SAME PLACE.

DESIGN FOR A GAME-BOARD.

SPECIFICATION forming part of Design No. 33,845, dated January 1, 1901.

Application filed December 3, 1900. Serial No. 38,575. Term of patent 14 years.

To all whom it may concern:

Be it known that I, CHARLES E. RANDALL, a citizen of the United States, residing at Atlanta, in the county of Fulton and State of Georgia, have invented and produced a new and original Design for Game-Boards, of which the following is a specification, reference being had to the accompanying drawings, forming a part thereof.

The leading feature of my design consists in a series of concentric squares of diminishing diameter having their sides parallel with the edges of the board, which is also square in form. These concentric squares are crossed by a cruciform body consisting of two pairs of parallel lines, the pairs respectively extending between the centers of the opposite sides. The four arms of the cruciform body are subdivided into squares, and these subdivisions are ornamented with one or more small figures.

Referring to the drawings, Figure 1 is a plan

view of a game-board embodying my design, and Fig. 2 is a sectional view of the same.

In the said drawings, 1 indicates the body 25 of the board, and 2, 3, 4, 5, and 6 indicate the concentric squares of diminishing diameter. The cruciform body is made up of two parallel lines 7, connecting the centers of two opposite sides and two similar parallel lines 8 at 30 right angles thereto and connecting the centers of the two opposite sides. This body is divided into squares, as shown, each containing figures 9.

Having thus fully described my invention, 35 what I claim as new, and desire to secure by Letters Patent, is—

The design for a game-board, as herein shown and described.

CHARLES E. RANDALL.
